UNITED STATES PATENT OFFICE.

HUGH BURGESS, OF ARDMORE, PENNSYLVANIA.

APPARATUS FOR RECOVERING SODA.

SPECIFICATION forming part of Letters Patent No. 429,417, dated June 3, 1890.

Application filed September 23, 1889. Serial No. 324,722. (No model.)

To all whom it may concern:

Be it known that I, HUGH BURGESS, a subject of the Queen of Great Britain, and a resident of Ardmore, in the county of Montgomery and State of Pennsylvania, have invented a new and useful Improvement in Apparatus for Evaporating and Calcining Solutions; and my invention consists in certain novel apparatus and combination of apparatus, of which the following is a true and exact description, due reference being had to the drawings which accompany and form part of this specification, and in which similar letters denote similar parts.

15 My invention relates to that class of apparatus in which the liquid is evaporated in a rotary evaporator subject to direct action of the heat, and the semi-liquid is then passed from this evaporator into a rotary incinerator; and it consists, essentially, of interposing a water-back between the rotary evaporator and rotary incinerator, so as to avoid the direct action of a too great heat at the mouth of the evaporator.

25 It also consists in the interposition of a lip between the evaporator and incinerator by which the liquid is carried from the evaporator into the incinerator. This lip is a water-lip—that is, water is caused to pass through it, so as to keep its temperature below melting-point.

In the drawings, Figure 1 is a longitudinal sectional view of my improved apparatus. Fig. 2 is a section on line $x-x$, Fig. 1, in direction of the arrow. Fig. 3 is a modified form of Fig. 2, showing the water-lip secured to the water-back. Fig. 4 is a section on line $y-y$, Fig. 1, in direction of the arrow.

A is the furnace carried by the wheels a . 30 a' is the fire-chamber. Beneath this fire-chamber is the air-inlet-chamber a^2 , which has a passage a^3 , through which air is carried around the fire-chamber and highly heated, and passing out through the passage a^4 directly over the mouth of the flue B, which leads from the fire-chamber, so that the products of combustion are provided with a fresh supply of heated air to cause a more perfect combustion in the incinerator of the gases 45 from the furnace A and those generated in the incinerator by the combustion of the organic matter in the incinerated mass.

C is a water-jacket, the water passing continuously through the pipe e^4 and passing out through the pipe e^3 . This water-jacket forms 55 the subject-matter of an application already filed by me, and therefore is not claimed in this application. The flue B and air-passage a^4 both pass through the water-jacket C.

D is a rotary vessel, preferably made cylindrical. This cylinder D may be constructed of a plate or cast-iron shell lined in the interior with fire-brick, and is rotated by means of a sprocket-chain from the source of power operating upon the sprocket-wheel d' . 65 This cylinder has projecting bands d^3 , which rest upon the friction rolls or wheels d^4 .

E is a water-jacket interposed between the cylinder D and the evaporator F. This water-jacket is supported by means of the 70 rods e , which are secured at one end to the lugs e' on the water-jacket and at the other end to beams or other suitable support above the cylinders. This water-jacket is so supported that it rests between and in line with 75 the two cylinders and has the opening or passage e^2 for the products of combustion to pass through.

e^3 is the inlet-pipe for the water to the water-jacket and e^4 the outlet-pipe for the 80 water-jacket. Water is constantly passed through this jacket.

E' is the water-lip by which connection is made between the cylinders D and F, the liquid reduced in the evaporator F passing 85 by means of this water-lip from the evaporator to the incinerator D. This water-lip may be supported either as shown in Fig. 2 or as shown in Fig. 3. In Fig. 2 the water-lip is supported by the supports e^5 , which rest upon 90 the base upon which the apparatus is supported. In Fig. 3 the water-lip E' is secured to the water-jacket E by means of bolts or water-connection e^6 . In the latter case the water-lip is in direct water communication 95 with the jacket E. In Fig. 2, which represents the water-lip not in water communication with the jacket E, the water is circulated through this water-lip, passing in through the pipe e^6 and out through the pipe e^7 . This 100 water-jacket is so supported that it forms a surface upon which the liquid passes from the cylinder F to the cylinder D.

F is a cylinder of smaller diameter and

greater length than cylinder D. This cylinder is rotated by a sprocket-chain from the source of power operating upon the sprocket f^2 , surrounding said cylinder F. This cylinder F has the projecting bands f^4 , which rest upon the friction pulleys or wheels f^5 . This cylinder may be constructed in the manner described for cylinder D. G is a tube leading from the funnel g to said cylinder F.

10 H is a pipe leading from the liquid-reservoir I to the funnel g.

As shown in the drawings, F is the rotary evaporator and D is the rotary incinerator. K is a flue to carry off the products of combustion to the stack or chimney k. The products of combustion from the furnace pass through the cylinder D, through the opening in the water-jacket, and into and through the cylinder F and flue K and escape through the stack or flue k.

15 The operation is as follows: The fire-brick or furnace A and water-jacket are brought to the face of the cylinder D and water passed through the water-jacket E and water-lip E', and the cylinders D and F caused to rotate.

20 The spent or other liquid to be treated is admitted through the funnel g and into the cylinder E, and the products of combustion passing through this cylinder, as hereinbefore described, cause an evaporation of the waste from the liquid, increasing its specific gravity. The rotation of the evaporator F diffuses the liquid around the interior surface and brings it into contact with the heated gases passing through the evaporator. The cylinder F is slightly inclined, as shown in the drawings, so that the liquid will move slowly through it, and it is obvious that the same object can be attained if the exterior of the cylinder be in a

25 horizontal line and the interior be slightly flaring. The liquid greatly concentrated by the treatment in the rotary evaporator passes over the water-lip E' into the incinerator D. The water-jacket E, which is interposed be-

30 tween the rotary D and the rotary F, prevents a too great action of the heat at this point, which is very desirable, as in many cases if this jacket were omitted the heat would be so great that the brick-work of the evaporator would become too highly heated at its edge next to the incinerator. The incineration of the liquid is completed in the rotary D, and the solid residue is delivered at the open space below the water-jacket C. The

35 object of the use of the water-jacket E and the water-lip E' interposed between the two rotaries has been fully described hereinbefore, and its advantages are obvious. The incinerated material passes out from the bottom

40 of the incinerator D at the point L into the reservoir I, from which it can be removed for such further use as is desired. The two rotaries are shown in line, but they can be placed at any desired angle with each other,

45 provided that the liquid from the first rotary is delivered into the second rotary, and I can

use a number of evaporators in connection with a common incinerator; or I may use several evaporating-cylinders connecting with each other and with an incinerator.

I do not intend to limit myself to the specific means described for rotating the cylinders. It is preferable, though not essential, that the incinerator and evaporator should be rotated at different speeds, the evaporator being the more rapidly rotated cylinder. It is preferable that the incinerator should be of greater diameter than the evaporator. With some classes of liquids it is essential that the completion of the operation should take place farthest from the source of heat, in which case the apparatus will be reversed, and the incinerator placed the farthest from the furnace A, when the evaporator will be the cylinder contiguous to said furnace.

50 My apparatus is especially advantageous for recovering waste alkaline from spent liquids produced in making paper-pulp; but it can be used with equal advantage for the recovery of any valuable solid matter from a liquid or semi-liquid.

I do not claim in this application the combination of a rotary evaporator and a rotary incinerator, said evaporator opening into said incinerator, whereby the liquid is increased in specific gravity in the evaporator and incinerated in the incinerator; nor do I claim in this application the combination of a rotary evaporator and a rotary incinerator, a combustion-chamber between said evaporator and said incinerator, both said evaporator and incinerator opening into said combustion-chamber, as these claims form the subject-matter and are specific claims in a certain application filed by me November 10, 1888, Serial No. 290,452.

Having now fully described my invention, what I claim, and desire to protect by Letters Patent, is—

1. In combination, two or more rotary cylinders, a furnace in front of the mouth of one of said cylinders, and a water-jacket interposed between said rotary cylinders.

2. In combination, two or more rotary cylinders opening into each other, a furnace in front of the mouth of one of said cylinders, and a water-jacket interposed between the mouths of said rotary cylinders.

3. In combination, two or more rotary cylinders, a furnace in front of the mouth of one of said cylinders, said cylinders opening into each other, and a water-jacket interposed between the mouths of said cylinders, the products of combustion from the furnace passing through said cylinders and water-jacket.

4. In combination, two or more rotary cylinders, a furnace in front of the mouth of one of said cylinders, and a water-lip connecting said cylinders one with the other.

5. In combination, two or more rotary cylinders, a furnace in front of the mouth of one of said cylinders, a water-lip connecting said

cylinders one with the other, and a water-jacket interposed between the mouths of said cylinders.

6. In combination, two or more rotary cylinders, a furnace in front of the mouth of one of said cylinders, water-lips connecting said cylinders one with the other, and water-jackets interposed between the mouths of said cylinders, the water-lips being secured to the water-jackets respectively.

7. In combination, two or more rotary cylinders, a furnace in front of the mouth of one of said cylinders, a water-jacket interposed

between the furnace and the mouth of said cylinder, water-lips connecting said cylinders 15 one with the other, and water-jackets interposed between the mouths of said cylinders.

In testimony of which invention I have hereunto set my hand, at Philadelphia, Pennsylvania, this 13th day of September, A. D. 20 1889.

HUGH BURGESS.
